UNITED STATES PATENT OFFICE.

HERMANN F. W. LIEBMANN, OF CHICAGO, ILLINOIS, ASSIGNOR OF ONE-HALF TO HERMANN RENDTORFF, OF SAME PLACE.

CAR-COUPING LINK.

SPECIFICATION forming part of Letters Patent No. 249,877, dated November 8, 1881.
Application filed September 27, 1881. (No model.)

To all whom it may concern:

Be it known that I, H. F. W. LIEBMANN, of the city of Chicago, county of Cook, and State of Illinois, have invented certain Improvements 5 in Coupling-Links for Cars, of which the following is a specification.

My invention relates to an improvement upon such coupling-links as are commonly used for coupling freight and other cars for railroads. 10 One end of such links is usually inserted into one of the draw-heads and a pin passed down through it and the link, while the other end is held and guided by the hand up or down or sideways, in order to secure its entrance into 15 the other draw-head as it approaches to be coupled.

My improvement consists of providing a strong cross-bar for the link, which is oblong in form, not only to render the link stronger, 20 but also to furnish a bearing or base for a handle, which may be made in one piece with such cross-bar; or it may extend through a hole in it above and below the cross-bar sufficiently for the convenience of the operator.

25 In the drawings, Figure 1 represents perspectives of two draw-heads and my improved link in position in one of the draw-heads, and Fig. 2 a central vertical section of the two draw-heads and the link in position after coupling 30 has been effected.

C and C' are the draw-heads, and B a pin inserted down through draw-head C and one end of link A, which is oblong in form, and is divided into two equal compartments by a 35 broad and strong cross-bar, D, which is designed not only to strengthen the link, but also to furnish a proper base and bearing for the handle a, which extends so far above and so far below the link and draw-heads as to enable the 40 operator to seize hold of it, either above or be-

low, and guide and control it in the act of coupling with perfect safety.

The link A and its cross-bar D and handle a may be made in one piece or otherwise.

I am aware that H. A. Barnes, in his Letters Patent of the United States, dated May 13, 1862, for improvement in shackles for railroad-cars, shows a link without a cross-bar, and provided with a half-link extending across and above the main link, and attached to the sides 45 of the same midway its length; and that W. E. Twining, in his like Letters Patent, dated March 24, 1868, for a car-coupling, shows an oblong link without a central cross-bar, but having 50 two bars or handles, one on each side, extending 55 laterally from the sides of the link; and that W. W. Haver, in his like Letters Patent, dated September 16, 1873, for a car-coupling, shows a link provided with a cross-bar designed to support a short standard, which is slotted to 60 bear an arm, a short shaft, and another arm, and a pivoted rod, by means of all of which the link can have merely vertical motion imparted to it in the act of coupling and uncoupling; and I disclaim these three several constructions; and 65

What I do claim as my invention, and desire to secure by Letters Patent, is—

The combination of the link A, provided with the strong central cross-bar, D, and the 70 handle a, fixed into the cross-bar and extending so far above and below the draw-heads as to enable the operator to take hold of it in the act of coupling and guide the free end of the link with safety, and the draw-heads C 75 and C', substantially as described.

H. F. W. LIEBMANN.
